UNITED STATES PATENT OFFICE.

ANDREW A. KRAMER, OF KANSAS CITY, MISSOURI.

TANK.

Application filed April 26, 1922. Serial No. 556,569.

To all whom it may concern:

Be it known that I, ANDREW A. KRAMER, a citizen of the United States, residing at Kansas City, in the county of Jackson and 5 State of Missouri, have invented certain new and useful Improvements in Tanks; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to tanks and particularly to tanks of relatively large capacities.

The invention is particularly adapted for use in connection with large oil tanks where 20 the roof area is considerable, the roofs of such tanks having a tendency to sag and it is a more or less engineering problem to build a tank of sheet metal and properly support the roof.

25 My invention contemplates the provision of means whereby the essential parts of the tank can be constructed or fabricated in the factory and sent out into the fields where they may be conveniently erected 30 to provide a tank of considerable area.

The particularly novel features of the invention will be apparent by reference to the following description in connection with the accompanying drawings, in which—

35 Fig. 1 is a view partly in elevation and partly in section, showing a tank constructed in accordance with my invention, the interior supporting means for the roof being shown in elevation.

40 Fig. 2 is an enlarged fragmentary view of the prop, part of the roof being shown in section.

Fig. 3 is a cross sectional view on the line 3—3 of Fig. 2.

45 Fig. 4 is a fragmentary detail view of one of the struts constituting the top, and the tie rod therefor.

50 Fig. 5 is a sectional view through a slightly modified form of strut tie plate and girder brace, and

Fig. 6 is a further modified form of the girder brace and strut tie plate.

Referring now to the drawings by numerals of reference:

55 1 designates the vertical wall of a tank having at its upper end an outwardly ex-

tending flange 2, upon which the outer edge of the roof may be supported. The center of the roof is adapted to be supported by a prop. The prop is shown as comprising a 60 centrally located standard or pipe 3, having at its upper end a central roof sheet comprising a conical disk 4, the convex portion of which is uppermost and the disk is provided at its edge with a depending bracing 65 flange 5.

Below the disk or roof sheet 4 is welded a sleeve 6, having an outwardly extending flange 7 and between it and the roof sheet 4 is another sheet 8. The flanges on the 70 two sheets may be fastened together if desired, the roof sheet 4 having a central opening through which the upper end of the standard or pipe 3 projects.

The roof sheet 4 is reinforced by a supporting cone 9, which is inverted with respect to the roof sheet 4 and which has a central opening 10 through which the standard 3 extends, the standard being provided with adjustment openings or holes 11, 75 through which a pin 12 may pass to hold the cone in any adjusted position, it being understood that when the cone 9 is on the standard, it may be pushed up against the roof sheet 4 and then held in place by the 80 pin 12.

The standard 3, which may consist of a pipe of suitable diameter, carries a step or platform 13 at its lower end and slidable on the standard 3 is a sleeve 14, to which may 90 be welded a plurality of upwardly disposed, radial struts or braces 15, and the braces preferably consist of two parts, the lower member of each of which is hollow to receive the rod 16, constituting the upper half of 95 the brace. The upper half of each brace is fastened to depending tie plates, which also constitute reinforcements for the roof, as will be presently explained.

Welded to the core 9 and extending downwardly therefrom are tie rods 17, which are received in the sleeves 18, integral with the lower members of the struts, as seen in Fig. 4. The lower ends of the upper members 16 of the struts may be fastened to the upper ends of the lower members of the struts by bolts 19, and the lower ends of the tie rods 17 may be fastened to the tubular portion 18 by the bolts 20, as clearly seen in Fig. 4.

The roof consists of a plurality of circular rows of segments, the alternate circular

rows of segments being braced or supported from below, the remaining segments bridging the space between the braced segments and between the perimeter and a braced segment as well as between the roof sheet 4 and a braced segment, as will be presently explained. The rows are designated 21, 22, 23, 24 and 25.

Each segment consists of a seat 26, having a box-shaped girder 27 at one edge and a similar girder 28 at its opposite edge, the girder 28 being larger than the girder 27 so that when adjacent segments or roof sheets are brought together, the girder, which consists of a channel, of one roof sheet may receive the opposite edge of the adjacent roof sheet within it, that is, the two girders will be nested as shown in Fig. 3, and packing strips or blocks will be between the joints so that they can be fastened together to prevent leakage. By nesting the girder at one edge of each roof sheet with a similar girder of an adjacent roof sheet, the circular series or rows of roof sheets are secured together in a substantially ring-shaped unitary structure of considerable strength.

The second row 22 may have fastened to it by the fastening devices 29 which connect the two girders together, a depending girder brace and tie plate 30, shown as an angle, the flange 31 of which may be secured to the inner face of the small girder by the bolt 29. There will be a plate 30 depending from each nested set of girders and to each plate 30 will be fastened the upper end of the member 16 of a structure or brace 15. The upper end of the member 16 is shown in Fig. 2 as being flat, as at 32, and fastened to the plate 30 by a bolt 32'. The ends of the brace and tie plates 30 are reinforced with respect one to the other by cross braces shown as Z-beams 33, which have flanges on their ends fastened to the tie plates 30 by bolts 34 and 35 so that the second row 22 of segments are all fastened and braced together and supported from the adjustable sleeve 14 by the struts 15.

The spaces between the inner ends of the segments in row 22 and the perimeter of the plate 4 are bridged by a row 21 of segments which have their inner ends overlapping the outer edge of the roof sheet 4 and which are packed by the packing blocks 36, the packing strips being used if desired so that there will be no leakage from the roof sheet 4 into the tank.

The outer edges of the segments in the row 21 overlap the roof sheets in the row 22, and, of course, their girders are nested over the girders in the row 22, the overlapping edges of the roof sheets in row 21 shedding onto the roof sheets in row 22.

Spaced from the perimeter of the row 22

is a row 24 of roof sheets constructed substantially like those described in the row 22 and they also have depending brace and tie plates 30 to which the upper ends of the outwardly inclined braces or struts 37 are connected, the lower ends of the struts 37 being supported on the inturned flange 38 of the circular irons 39 (see Fig. 1).

The outer ends of the roof sheets in row 24 are also supported by the tie and brace rods 40 (see Fig. 1). The row 24 terminates short of the wall 1 and the space is bridged by the row 25, which corresponds to the row 21 and since 24 is also spaced from the outer end of the row 22, the gap is bridged by the plates 23, which correspond to the row 21. Therefore, a complete roof is provided, which may be conveniently supported by the struts or braces 15 and 37.

The sleeve 14 is vertically adjustable on the center pole or standard 3 and beneath it is a jack sleeve 41, the upper edge of which is substantially the diameter of the sleeve 14 and the lower edge of which is provided with a circumferential, outwardly disposed flange or foot 42, beneath which the jack may be introduced so that force can be applied to the sleeve 41 to raise it and since its upper edge will contact with the lower edge of the sleeve 14, it is apparent that the sleeve 14 can be adjusted vertically, even against the weight of the roof exerted against the struts which it carries. Therefore, when the parts are assembled, a jack can be placed under the foot 42 and the prop raised so that the roof plates will be put under slight tension and will have the proper angle to form the water shed. When the sleeve 14 is adjusted at the proper height, it may be secured there by a bolt 43 which extends through the sleeve and through the adjustment openings 44.

The bottom of the tank may be reinforced by an angle 45. The prop is so constructed and associated with the roof that a substantially umbrella bracing is provided with alternately braced and bridging roof plates.

46 are tie rods which are transversely arranged to connect the struts 15 together so as to resist the tendency of the struts to spread.

In Fig. 5 the tying and bracing plate 30' is integral with the girder in contra-distinction to the separate brace plate 30 shown in Fig. 3.

In Fig. 6 instead of the brace 30, a channel 30'' is bolted in between the sides of the girders to both brace them and serve as a tying-in plate. In other respects, all of the tying-in plates 30, 30' and 30'' are alike.

It will be seen that the parts can be readily constructed in the factory and sent out into the field where they may be conveniently assembled to form a tank of relatively large capacity and simple construction.

What I claim and desire to secure by Letters Patent is:

1. A tank comprising an enclosing wall, a standard, a roof sheet adjustably mounted on the standard, other roof sheets supported on the adjustable roof sheet and on the enclosing wall, struts adjustably mounted on said standard and connected with said other roof sheets, and means for anchoring said adjustable roof sheets and said struts in adjusted position on said standard.

2. A tank comprising an enclosing wall, a standard, a roof sheet adjustably mounted on the standard, other roof sheets supported on the adjustable roof sheet and on the enclosing wall, struts adjustably mounted on said standard and connected with said other roof sheets, an adjustable roof sheet support, and tie rods mounted on said struts and connected with said adjustable roof sheet support.

3. A tank comprising an enclosing wall, a standard, a roof sheet adjustably mounted on the standard, other roof sheets supported on the adjustable roof sheet and on the enclosing wall, struts adjustably mounted on said standard and connected with said other roof sheets, an adjustable roof sheet support, tie rods mounted on said struts and connected with said adjustable roof sheet support, and means for elevating the struts to lift the roof sheets.

4. A tank comprising a circular wall, a roof supported by the wall, a center prop for the roof comprising a standard, a cone at the upper end of the standard, the flared portion of which supports the center of the roof, means for adjusting the cone on the standard, radial props adjustably mounted on the standard, the upper ends of the props engaging the roof, and tie rods for the props, each tie rod being connected to an intermediate portion of the prop and to the cone.

5. A tank comprising a circular wall, a roof supported by the wall, a center prop for the roof comprising a standard, a cone at the upper end of the standard, the flared portion of which supports the center of the roof, means for adjusting the cone on the standard, radial props adjustably mounted on the standard, the upper ends of the props engaging the roof, tie rods for the props, each tie rod being connected to an intermediate portion of the prop and to the cone, and additional props supported by the interior of the wall and having their upper ends supporting the roof near the perimeter thereof.

6. A prop for tank roofs comprising a standard, a sleeve vertically adjustable on said standard, radial, upwardly disposed struts carried by the sleeve, and a second sleeve mounted on the standard below the first named sleeve and having lifting jack

engaging portions whereby a lifting jack may be placed under the sleeve to raise the strut-carrying sleeve on the standard.

7. A prop for tank roofs comprising a standard, a sleeve vertically adjustable on said standard, radial, upwardly disposed struts carried by the sleeve, a second sleeve mounted on the standard below the first named sleeve and having lifting jack engaging portions whereby a lifting jack may be placed under the sleeve to raise the strut-carrying sleeve on the standard, and means for holding the strut-carrying sleeve in any adjusted position with respect to the standard.

8. A tank comprising a space surrounding wall, a center prop within the tank comprising a standard, spaced rings consisting of roof sheet plates, ring-supporting means on the standard comprising struts, ring-supporting means carried by the wall, and additional rings bridging the spaces between the supported rings and the space between a supported ring and the wall, and also a space between one of the supported rings and the center of the tank.

9. A tank comprising a surrounding wall, a center prop within the tank consisting of a standard, radial, upwardly disposed props carried by the standard, roof sheets having depending plates engaged by the upper ends of the props, props carried by the wall, roof sheets having depending flanges engaging the props supported by the wall, the two sets of roof sheets being spaced apart, and additional roof sheets bridging the gap between the supported roof sheets.

10. A tank comprising a surrounding wall, a center prop within the tank consisting of a standard, radial, upwardly disposed props carried by the standard, roof sheets having depending plates engaged by the upper ends of the props, props carried by the wall, roof sheets having depending flanges engaging the props supported by the wall, the two sets of roof sheets being spaced apart, additional roof sheets bridging the gap between the supported roof sheets, and means for transversely connecting the flange of one sheet to the flange of another sheet.

11. A tank comprising a surrounding wall, a center prop within the tank consisting of a standard, radial, upwardly disposed props carried by the standard, roof sheets having depending plates engaged by the upper ends of the props, props carried by the wall, roof sheets having depending flanges engaging the props supported by the wall, the two sets of roof sheets being spaced apart, additional roof sheets bridging the gap between the supported roof sheets, means for transversely connecting the flange of one sheet to the flange of another sheet, and means for tying the props one to the other.

12. A tank comprising a surrounding wall, a center prop within the tank consisting of a standard, radial, upwardly disposed props carried by the standard, roof sheets having depending plates engaged by the upper ends of the props, props carried by the wall, roof sheets having depending flanges engaging the props supported by the wall, the two sets of roof sheets being spaced apart, additional roof sheets bridging the gap between the supported roof sheets, means for transversely connecting the flange of one sheet to the flange of another sheet, means for tying the props one to the other, and tie rods supporting the props from the top of the standard, the tie rods engaging the props intermediate their end. 15

In testimony whereof I affix my signature.

ANDREW A. KRAMER.
